(57) **CLAIM**

The ornamental designs for a Euro-top mattress design, as shown and described.

DESCRIPTION

FIG. 1 is a perspective view of a first embodiment of the Euro-top mattress design.

FIG. 2 is a side view of the Euro-top mattress design of FIG. 1, identical to the opposite side view thereof.

FIG. 3 is an end view of the Euro-top mattress design of FIG. 1.

FIG. 4 is a top view of the Euro-top mattress design of FIG. 1.

FIG. 5 is a bottom view of the Euro-top mattress design of FIG. 1.

FIG. 6 is a perspective view of a second embodiment of the Euro-top mattress design.

FIG. 7 is a side view of the Euro-top mattress design of FIG. 6, identical to the opposite side view thereof.

FIG. 8 is an end view of the Euro-top mattress design of FIG. 6.

FIG. 9 is a top view of the Euro-top mattress design of FIG. 6; and,

FIG. 10 is a bottom view of the Euro-top mattress design of FIG. 6.

The broken lines are for environmental purposes only and form no part of the claimed design. The angled shade lines in FIGS. 6-9 depict the color brown.
